UNITED STATES PATENT OFFICE.

JOHN M. DRIVER, OF PHILADELPHIA, PENNSYLVANIA.

CONTINUOUS ARTICLE FORMING AND PRINTING MACHINE.

Application filed December 23, 1921. Serial No. 524,494.

To all whom it may concern:

Be it known that I, JOHN M. DRIVER, a citizen of the United States, residing in Philadelphia, Pennsylvania, have invented 5 a Continuous Article Forming and Printing Machine, of which the following is a specification.

My invention relates to machines for forming and printing paper articles such as bags 10 and envelopes.

The principal object of this invention is to provide a machine for forming and printing having a continuous operation and so built as to insure a proper positioning of 15 the printed matter upon the finished article.

Hitherto in continuous forming and printing machines there has been considerable difficulty in obtaining a proper positioning of the printed matter upon the article, and 20 as a result it has been common practice first to form the article in a forming machine and thereafter to manually convey the articles to an independent printing machine, this being the only way in which a successful 25 article could be obtained.

I have provided a machine to which the blank material from which the bags, envelopes or other articles are to be formed is fed at one end, said material being received 30 properly formed and printed from the other end of the machine with the printed matter in the desired proper position upon the article, the machine insuring great rapidity of action and a perfect finished article.

35 The invention will be more readily understood by reference to the attached drawings, in which:

Figure 1, is a diagrammatic side elevation of a machine made in accordance with my 40 invention;

Fig. 2, is a fragmentary section illustrating the details of the feed from the forming mechanism to the conveyer;

Fig. 3, is a plan view of the receiving end 45 of the printing mechanism;

Figs. 4 and 5, are, respectively, front and side elevations of the receiving end of the printing mechanism;

Fig. 6, is a fragmentary section of one 50 end of the conveyer and of the receiving end of the printing mechanism, and

Figs. 7 and 8, are fragmentary sections enlarged illustrating elements and operation of the receiving end of the printing 55 mechanism.

In the drawings, 1 indicates a frame in

which is supported mechanism for forming, in the present instance, paper bags or envelopes, said mechanism being of any of the standard and well known makes and accordingly not described herein in any detail. Adjacent the frame 1 is a frame 2 which carries the operating elements of a pair of endless belts 3 and 4, which together constitute an endless conveyer adapted to receive 60 the formed articles from the forming mechanism and to convey them to printing mechanism established in a frame 5, in the present instance adjacent that side of the frame 1 opposite to the frame 5, the conveyer also 65 functioning to effect an initial drying of the adhesive employed in forming the articles to the extent of setting the adhesive and assuring its holding the parts together during 70 succeeding operations.

In the present instance the conveyer constituted by the endless belts 3 and 4 passes around a pulley wheel 6 mounted in the frame 2 over a roller 7 also mounted on the frame and over and under a set of guide 75 rollers 8, 8, which latter are mounted on a superframe 9 carried by the frame 1. The belts travel in the direction of the arrows in Fig. 1, and it will be noted that in its passage around the pulley 6 and past the 80 guide rolls 7 and 8, the belt 3 overlies the belt 4 at the article-receiving end. As, however, the belts pass from the last of the rollers 8, the belt 3 passes under a guide roll 10, while the belt 4 passes under a companion guide roll 11 in the opposite direction, the belt 3 passing under and over guide rolls 12, 12, carried by the frame 9 and around a guide roll 13 supported by the frame 2 to a guide roll 14, from which it 85 again passes to the pulley 6, while the belt 4 after passing around the guide roll 11 passes over a roll 15 mounted on the frame 9, and thence over and around rolls 16, 16, carried by the frame 2 to a roll 17 forming 90 a companion roll to the roll 14 which it underlies.

As previously stated, the conveyer is adapted to receive formed articles from the forming mechanism and to conduct them to 105 the printing mechanism. The manner in which a formed article is fed to the conveyer is most clearly shown in Fig. 2, which shows an envelope or bag 18 passing between a pair of feed rolls 19, 19, which latter direct the article onto the belt 4 and between 110 the companion rollers 14 and 17, the envelope

lope 18 being thus confined between the two belts 3 and 4, and being carried along with them over the pulley 6 and the various guide rollers to the guide rolls 10 and 11, at which 5 point the belts 3 and 4 separate, permitting the article to drop into a properly constructed receptacle in the printing mechanism.

The receptacle for the printing mechanism 10 is illustrated in Figs. 3 to 8, inclusive, and comprises a pair of adjustable side pieces 20, 20, which flare outwardly at the top, as best shown in Fig. 4, said side pieces having disposed therebetween a pusher head 21 of a 15 reciprocatory or oscillatory pusher element 22, the function of which will be described hereinafter.

Mounted on a rod 23 underlying the side pieces 20, 20, are a pair of fingers 24, 24, 20 which latter extend parallel to the lower edges of the side pieces 20 and constitute the floor of the receptacle.

Mounted upon a rod 25 and extending downwardly between the side pieces 20, 20, 25 is a flexible guide element 26, said guide element normally assuming the position in which it is shown in Fig. 7. It will be noted that the pusher element 21, which normally occupies a retracted position as shown in 30 Fig. 7, slopes rearwardly towards the top and away from the element 26, this pusher element together with the guide 26 and the side pieces 20, 20, insuring the upright positioning in the receptacle of the articles 35 charged from the conveyor between the rolls 10 and 11, which articles are indicated in the figures by the reference numeral 18, with the bottom edges of the article resting upon the fingers 24, 24, in which position the article is in condition to be fed to the printing mechanism.

As the articles drop from the conveyor into the receptacle of the printing mechanism, they are apt in the absence of suitable 45 dampening means to rebound from the fingers 24, such rebound on occasion being sufficient to interfere with the proper operation of the machine. To prevent this rebound I may provide, as shown in Fig. 7, brushes 50 18^a, 18^a, of camel's hair or the like extending inwardly toward each other from the opposed faces of the guide 26 and the pusher 21, said brushes meeting and constituting an efficient damper substantially preventing 55 rebound of the articles from the fingers while in no way interfering with the free entrance of the articles into the receptacle.

The pusher element 21 is adapted to be oscillated forwardly into a position illustrated in Fig. 8, and in operation this forward movement of the pusher occurs as each new article passes into the receptacle. This 60 forward movement of the pusher 21 has the effect of pushing the article 18 against the 65 guide element 26, which latter, as the pusher

advances, is flexed rearwardly as shown in Fig. 8, the article 18 being carried forwardly toward the ends of the finger elements 24, 24, until eventually the lower end of the article passes off of the end of the fingers. 70 In this position of the article, the lower edge thereof is gripped by an automatically operating clamp 27 upon a feeder roll 28 mounted in the frame 5, the article 18 thus being withdrawn from the receptacle by the 75 continued revolution of the feed roll 28, and being passed by the feed roll to the printing mechanism in well known manner. The feed roll 28 with its clamps is well known in printing mechanism of the type employed, 80 and the details of the roll and the clamps are accordingly not described.

In the present instance, reference being had to Fig. 8 of the drawings, the pusher element 22 is shown fixed to the end of an arm 41, which latter is connected by means of a link 42 to a fixed arm 43. The element 22 also has secured to its base an arm of a bell crank 44 on a rock shaft 45, there being secured to the latter a second arm 46 whose outer end carries a roller 47 disposed within the cam groove 48 of a cam plate 49. The plate 49 rotating with the shaft 50 upon which the roll 28 is mounted thus provides the movement to the pusher element. 95

It will be noted that by reason of the above described receiving means for the printing mechanism a proper disposition of the articles in the printing mechanism is insured, thereby eliminating all possibility of 100 a misplacement of the printed matter upon the article. It will further be noted that regardless of the position in which the bag is received from the forming mechanism by the conveyor, the receptacle insures the proper 105 positioning of the article before it passes to the printing mechanism.

As clearly shown in Fig. 1, the forming mechanism, the printing mechanism and the conveyor are all operated from a single 110 source of power, and are so connected as to insure an absolute synchronism of movement, this being essential for the proper operation of the machine. In the present instance, the source of power is an electric 115 motor 30, which is connected through a variable speed transmission device 31 of any suitable construction with the forming mechanism through a belt or other connector 32 and with the conveyor elements through 120 a belt or other suitable connector 33, the forming mechanism being connected with the printing mechanism by means in the present instance of sprockets 34, 35, 36 and 37, and associated sprocket chains 38, 39 125 and 40.

I claim:

1. In a machine of the type specified, the combination with article forming mechanism, of printing mechanism, conveying 130

means for passing formed articles from the forming mechanism to the printing mechanism, and a feeding device disposed to receive articles in an upright position from said 5 conveying means and moving the same laterally into contacting relation with said printing mechanism.

2. In a machine of the type specified, the combination with article-forming mechanism, of printing mechanism, a conveyer comprising a pair of endless belts adapted to receive therebetween an article whereby the latter is conveyed from one point to another, means associated with the forming mechanism for passing a formed article between the said endless belts, and means operatively associated with the printing mechanism and comprising a receptacle for receiving a conveyed article from the belts and having a 20 movable wall feeding it toward the printing mechanism.

3. In a machine of the type specified, the combination with article forming mechanism, of printing mechanism, means for conveying and partially drying formed articles from the forming mechanism in reversed position to the printing mechanism, and means associated with the printing mechanism for receiving said articles when released from 25 the conveyer in a substantially vertical plane and feeding them in a substantially horizontal plane to the printing mechanism.

4. In a machine of the type specified, the combination with article forming mechanism, of printing mechanism, a conveyer adapted to convey formed articles from the forming mechanism to the printing mechanism, a receptacle disposed to receive conveyed articles in a substantially vertical position from the conveyer, means within said receptacle for preventing rebound of said articles therein, and means associated with the printing mechanism for feeding said articles laterally toward said mechanism.

45 5. In a machine of the type specified, the combination with article forming mechanism, of printing mechanism, a conveyer, means for feeding the formed articles from the forming mechanism to the conveyer, a 50 receptacle having means to support an article received from the conveyer in substantially vertical position, and an associated movable member disposed parallel to the article for feeding the same toward the 55 printing mechanism.

6. In a machine of the type specified, the combination with article-forming mecha-

nism, of printing mechanism, a conveyer adapted to receive articles from the forming mechanism and to convey them to the printing mechanism, means for receiving the said conveyed articles from the conveyer comprising a substantially rectangular, funnel-shaped receptacle, one side of which is resilient and the opposite side movable toward 60 the printing mechanism whereby contained articles are passed to the said mechanism.

7. In a machine of the type specified, the combination with article-forming mechanism, of printing mechanism, a conveyer 70 adapted to receive articles from the forming mechanism and to conduct them to the printing mechanism, a receptacle associated with the printing mechanism for receiving the conveyed articles, means for passing articles 75 from the receptacle to the printing mechanism, and means individually supporting the articles and for preventing rebound of the conveyed articles from the bottom of the receptacle.

8. In a machine of the type specified, the combination with article forming mechanism, of printing mechanism, an interposed conveyer, a feeding receptacle disposed to receive articles delivered from said conveyer, 85 a yielding wall at the side of said receptacle next the printing mechanism, and an opposite movable wall having driving relation with the printing mechanism.

9. In a machine of the type specified, the 90 combination with article forming mechanism, of printing mechanism, an interposed conveyer, a feeding receptacle disposed to receive articles delivered from said conveyer, a yielding wall at the side of said receptacle 95 next the printing mechanism, an opposite movable wall having driving relation with the printing mechanism, and frictional means carried by said walls and disposed to prevent rebound of an article upon its delivery into said receptacle.

10. In a machine of the type specified, the combination with article forming mechanism, of printing mechanism, an intermediate conveyer, a feeding receptacle having adjustable side walls and a supporting bottom, a yielding wall for said receptacle next the printing mechanism, an opposite movable pivotally mounted wall disposed to travel toward and from the printing mechanism, and 110 a timed driving connection between said last mentioned wall and the printing mechanism.

JOHN M. DRIVER.
